UNITED STATES PATENT OFFICE.

JOHN S. GARMAN, OF ALLIANCE, OHIO.

SHOW-CASE.

No. 905,809.

Specification of Letters Patent.

Patented Dec. 1, 1908.

Application filed March 27, 1908. Serial No. 423,774.

To all whom it may concern:

Be it known that I, JOHN S. GARMAN, a citizen of the United States, residing at Alliance, in the county of Stark and State of Ohio, have invented certain new and useful Improvements in Show-Cases; and I do hereby declare that the following is a full, clear, and exact description of the same, reference being had to the accompanying drawing, making a part of this specification, and to the numerals and figures of reference marked thereon, in which—

Figure 1 is a perspective view of a case showing the same applied to use. Fig. 2 is a transverse section. Fig. 3 is a view looking toward the rear of the case, showing boxes containing the goods to be exposed properly located in the left hand portion of the figure, and the boxes removed in the right hand portion. Fig. 4 is a detached view of one of the box holding bars. Fig. 5 is a view of one of the notch or rack bars.

The present invention has relation to show cases designed to hold any desired number of boxes containing goods such as crackers, cookies and other articles designed to be retailed from the boxes contained in the case.

Similar numerals of reference indicate corresponding parts in all the figures of the drawing.

In the accompanying drawing, 1 represents the case, which may be of any desired size and its front edge or portion is inclined from near the bottom of the case backward toward the top for the purpose of better exposing the goods contained in the boxes placed in the case, and also to hold in a closed position the doors 2 without the necessity of providing fasteners for said doors, but if desired suitable fasteners can be provided without departing from the nature of my invention.

The doors are preferably hinged at their bottom or lower edges as illustrated in the drawing. Within the case 1 are located a series of bars 3, or their equivalents, which bars are located substantially at right angles to the inclined front of the case 1, and at acute angles to the horizontal base 4 of the case 1, by which arrangement the opened boxes containing the goods designed to be retailed are brought into proper position to display the goods contained in said boxes, or in other words the bars 3 are inclined downward from the front of the case proper.

Upon the bars 3 are located and connected thereto the notched or toothed bars 5, which toothed bars are held in fixed relationship with reference to the inclined bars 3 by any suitable means. Upon the toothed bars 5 are located the box holding bars 6, which are provided with the ribs 7 located at the junction of the bars 6 and their right angled portions 7^a. Upon the bars 6 are located the lowermost portions of the boxes 8 and the right angled portions 7^a located against the backs of the boxes as best illustrated in Fig. 2. It will be understood by providing the bars 6 and forming the ribs 7, which ribs are designed to be seated in the desired notch of the notched bars 5, said bars will be held in fixed adjustment with reference to the bars 5 and in turn hold the boxes in proper position within the case 1.

The object and purpose in providing means for adjusting the box holding bars 6 is to so locate said bars that different sized boxes may be placed in the case, and at the same time bring the open portions in close relationship with reference to the hinged doors 2. The right angled portions 7^a are provided with apertures 9, through which apertures small nails 10 or their equivalents are passed and may be driven into the boxes thereby holding the boxes in proper relationship with reference to the bars 6.

For the purpose of providing means for connecting the inclined bars 3 intermediate the ends of the case 1 the upright bars 11 are provided, to which upright bars the inclined bars 3 are secured in any convenient and well known manner.

For the purpose of placing boxes in the case 1 and removing empty boxes therefrom the rear of the case should be formed open or provided with a suitable door. To the hinged doors 2 are attached the suspending chains 12 or their equivalents, which are designed to hold the doors in the position illustrated in Figs. 1 and 2 when the doors are open.

Having fully described my invention what I claim as new and desire to secure by Letters Patent, is—

1. In a show case, the combination of a case having a beveled front, doors hinged thereto, bars inclined downward and rearward from the beveled front of the case, toothed bars and plates adjustably connected to said toothed bars, substantially as and for the purpose specified.

2. In a show case, the combination of a case having a beveled front, doors hinged thereto, bars inclined downward and rearward from the beveled front of the case, 5 toothed bars and plates adjustably connected to said toothed bars, said plates provided with box holding extensions, substantially as and for the purpose specified.

In testimony that I claim the above, I have hereunto subscribed my name in the presence of two witnesses.

JOHN S. GARMAN.
